UNITED STATES PATENT OFFICE.

GEORGE A. CASPERS AND NATHANIEL S. DEUTSCH, OF NEW YORK, N. Y.

MILK-BOTTLE CAP.

1,163,968.

Specification of Letters Patent. Patented Dec. 14, 1915.

Application filed December 23, 1914, Serial No. 878,757. Renewed November 4, 1915. Serial No. 59,694.

To all whom it may concern:

Be it known that we, GEORGE A. CASPERS and NATHANIEL S. DEUTSCH, citizens of the United States, residing at New York, in the 5 counties of New York and Bronx, respectively, and State of New York, have invented a new and useful Milk-Bottle Cap, of which the following is a full, clear, and exact specification.

10 This invention relates to caps for milk bottles, and has for its object to allow for the expansion of the milk when it congeals or freezes without danger of breaking the bottle or exposing the projected portion of 15 the frozen mass to the outside air laden with dirt and germs.

A further object is to provide a cap for this purpose which may be easily applied and removed from the bottle, and which 20 may be inexpensively manufactured.

Other objects will appear as the description proceeds.

The invention will be first hereinafter described in connection with the accompanying 25 drawings, which constitute a part of this specification, and then more specifically defined in the claims at the end of the description.

In the accompanying drawings, wherein 30 similar reference characters are used to designate corresponding parts throughout the several views: Figure 1 is an elevation of the upper end portion or neck of a milk bottle having our improved cap applied thereto, the upper extremity of the bottle 35 neck and the cap being shown in section to better illustrate the construction of the latter. Fig. 2 is a similar view showing the position of the cap when the milk freezes 40 and projects itself above the mouth of the bottle, and Fig. 3 is a detailed perspective view of one means for holding the cap in position upon the neck of the bottle.

The milk bottle A illustrated in the drawings is of the ordinary type and form, having a bead *a* around its mouth, and an internal shoulder or seat *a'* for the usual closure or disk.

Our improved cap B consists of a disk *b* 50 similar to those now generally in use, and in addition to said disk a depending skirt portion, the lower end *b'* of which is secured around the mouth of the bottle below the

bead *a*. The upper or body portion *b*² of the skirt is made extensible by the use of accordion plaiting, the folds of which extend around the cap or skirt portion so as to permit the expansion in an upward direction as illustrated in Fig. 2.

The cap is fastened to the bottle by means 60 of a metal band C, best illustrated in Fig. 3, having an interlocking tongue *c*, or by any other suitable holding means adapted to retain the lower end portion *b'* of the cap around the neck of the bottle below the bead 65 *a*. The disk *b* is inserted in the mouth of the bottle so as to rest upon the seat *a'* when the bottle is filled, as shown in Fig. 1. If the milk freezes and projects itself above the top of the bottle, the disk *b* will be displaced and 70 raised upon the top of the frozen projecting portion and as said disk is thus raised, the accordion plaiting *b*² will open up or expand, as illustrated in Fig. 2. The frozen projecting portion will thus be inclosed and 75 protected by the cap against contamination.

Having thus described our invention what we claim as new and desire to secure by Letters Patent of the United States is:—

1. A bottle cap having a horizontally 80 plaited skirt portion the lower end of which is adapted to be secured around the neck of a bottle, the plaits permitting vertical expansion of the skirt portion without movement of the part secured around the 85 bottle neck.

2. A bottle cap having a disk to fit in the neck of a bottle, and a horizontally plaited skirt portion to be secured around the bottle neck, the plaits permitting vertical expansion of the skirt portion without movement of the parts secured around the bottle neck. 90

3. A bottle cap having a disk to fit in the mouth of a bottle, a skirt having a plaited portion to inclose the rim of the mouth of 95 the bottle, and a plain portion at the lower edge of the skirt to be secured around the neck of the bottle.

In testimony whereof we have signed our names to this specification in the presence 100 of two attesting witnesses.

GEORGE A. CASPERS.

NATHANIEL S. DEUTSCH.
